Inventor

H. L. Fischer.

UNITED STATES PATENT OFFICE.

HOWARD L. FISCHER, OF ST. PAUL, MINNESOTA, ASSIGNEE TO BROWN & BIGELOW, OF ST. PAUL, MINNESOTA, A CORPORATION OF MINNESOTA.

PENCIL.

Application filed July 2, 1920. Serial No. 393,661.

To all whom it may concern:

Be it known that I, HOWARD L. FISCHER, a citizen of the United States of America, residing at St. Paul, in the county of Ramsey 5 and State of Minnesota, have invented certain new and useful Improvements in Pencils, of which the following is a specification.

My invention relates to pencils, the primary object of which is to provide a 10 pencil with a sectional lead-propelling means removably held in the pencil casing to allow the different sections of the pencil to be removed independently.

A further object of the invention is in 15 means whereby the entire contents of the magazine can be withdrawn and to leave the pencil casing entirely empty when the lead-propelling mechanism in its entirety is withdrawn from the casing.

20 The invention further provides means whereby the lead-propelling mechanism cooperates with the pencil casing to form a magazine for extra marking leads giving a pencil of extremely simple construction and 25 wherein only a small number of parts are required.

It is also an object of the invention to provide frictional resilient means between the sections of the lead-propelling means to hold 30 the same against free movement and to take up the wear of the operating parts so that a uniform contact is provided between the parts.

In the drawings forming a part of the 35 specification

Figure 1 is a side sectional elevation of my pencil,

Figure 2 is a perspective view illustrating the extra marking leads distended from the 40 magazine when the same is opened,

Figure 3 is a perspective view of the operating section of the propelling means,

Figure 4 is a perspective view of the threaded section of the propelling means,

45 Figure 5 is a cross section on the line V—V of Figure 1,

Figure 6 is a detail of the forward end of the operating section, illustrating an alternative form,

50 Figure 7 is a perspective view of the lead carrier.

In the drawing the pencil A is provided with a casing 10 having a forward conical end 11 with an opening 12, at the apex of

the same through which the marking lead 13 55 extends when in writing position.

The casing 10 is formed of thin tubing and houses the lead-propelling mechanism B which is made up of the sectional members 14 and 15. The member 14 is formed of 60 thin tubing and is spaced from the casing 10 by the washer collar 16 attached to the forward or inner end of the member 14 while the rear end of the member 14 is connected detachably with the casing by the 65 closure head 17. Each of the members 16 and 17 are rigidly attached in a suitable manner to the member 14.

The member 14, is threaded throughout its length, the threads 18 being formed 70 therein by rolling or otherwise so as to form thread-projections on the inner surface of the member 14.

The member 15 is tubular and is formed with a longitudinal slot 19. An operating 75 head 20 is rigidly attached to the rear end of the member 15, said member carrying the lead-carrier 21 which is formed with a lead-receiving socket 22 on its forward end adapted to receive the butt end of the marking lead 13 while a spring tongue or arm 23 is formed projecting from the rear end of the carrier 21, the lead-carrier 21 is held against disengagement from the slot 19 by the shoulder 24 formed on the forward end 85 of the member 15. The member 15 together with the lead-carrier 21 is similar in construction and function to the member 16 and lead-carrier 18 in my patent application 90 Serial No. 391,409 filed June 24, 1920.

Lead-propelling mechanism being composed of the members 14 and 15, when put together, appears in the assembled position as illustrated in Figure 1. In this position the member 15 extends through the threaded member 14, the member 15 engaging the threads 18 of the member 14 frictionally and the lead-carrier 21 forming frictional resilient means between the members 14 and 15, the notches or threads 25 formed in the 100 carrier 21 engage the threads 18 of the member 14.

In the assembled position of the lead-propelling mechanism longitudinal slot 19 allows the member 15 to be withdrawn from the member 14 to determine the remaining unused lead in the pencil A as illustrated in dotted outline in Figure 1. The lead-car-

rier 21 forms a stop to limit withdrawing or longitudinal movement of the member 15 by engaging with the shoulder 24.

The lead-carrier 21 can be forced to slide longitudinally of the member 14 and in the member 15 when more than writing pressure is exerted against the marking lead 13 to release the same into the casing 10 to protect the marking lead against being broken when the pencil falls on the point or if otherwise struck on the writing point. When the carrier 21 is slid over the threads 18 it can again be readily picked up by the threads when the operating member 15 is rotated in either direction.

The operating member is rotated by engaging the head 20 to rotate the carrier 21 in the member 14 as it engages the threads 18 thus moving the carrier 21 longitudinally and rotatably in the pencil. The closure 17 rigidly attaches the member 14 against rotation in the casing 10 and closes the rear end of the magazine 26 formed about the propelling mechanism B.

The sections 14 and 15 of the lead-propelling mechanism are separable as illustrated by Figures 3 and 4, thus the operating member 15 can be withdrawn and separated from the member 14 without opening or disengaging the magazine member 14. This is an important feature of the invention as it protects the marking leads against falling out of the pencil when the member 15 is partly withdrawn from the member 14, and a separate closure 17 is provided for the rear end of the magazine.

When an extra or new marking lead is desired, the closure 17 is disengaged from the rear end of the pencil casing and the member 14 partially withdrawn from the casing, to distend the extra marking leads 27 so they can be easily engaged and removed from the magazine. By entirely withdrawing the operating mechanism B or the member 14 from the casing 10, the entire contents of the magazine is removed from the pencil casing.

Figure 6 illustrates an enlarged detail of the forward end of the member 15. The spring fingers 28 are formed integral with the member 15 and are adapted to engage against the outer surface of the washer 16 to hold a member 15 in addition to the frictional engagement between the members 14 and 15 so as to prevent free longitudinal movement of the same but allowing a separation of the members 14 and 15 when it is desired.

What I claim as new is:—

1. In a pencil, a casing having an opening adjacent the writing point, and a removable lead-carrying unit formed of detachable sections, one of said sections being adapted to cooperate with the casing to form a lead-carrying compartment, the other sec-

tion cooperating with the first section to present a lead through said opening at the writing point at will.

2. In a pencil, a casing having an opening adjacent the writing point, and a removable lead-carrying unit formed of separable sections, one of said sections being adapted to cooperate with the casing to form a circular lead-carrying compartment, the other section cooperating with the first section to propel and repel a lead in said unit and pencil. 70

3. In a pencil, a casing, and a lead carrying unit formed of sections, one of said sections being adapted to cooperate with the casing to form a lead carrying compartment, the other section being operative to present a lead at the writing point of the casing, said sections being removable from said casing collectively and selectively. 80

4. In a pencil, a casing, and a lead operating unit formed of sections normally held in said casing, said sections being removable from the casing selectively and collectively. 85

5. In a pencil, a casing having an opening adjacent the writing point, and a sectional lead-carrying unit, one of said sections being adapted to cooperate with the casing to form a lead-carrying compartment, the other section being operative to present a lead through said opening, said sections being removable from the casing collectively, said latter section being removable independently of the first section. 95

6. In a mechanical pencil, a casing, a removable sectional lead operating unit and means for releasably locking the sections of the unit against relative longitudinal movement to each other. 100

7. In a pencil, a casing having an opening adjacent the writing point, and a sectional lead-carrying unit, forming a lead-propelling mechanism, one of said sections cooperating with the casing to form a lead-carrying compartment and having a closure for said compartment on its rear end and the other of said sections being independently separable from said casing without opening said lead compartment, said last section forming the operating means for said propelling mechanism, and adapted to carry the marking lead in writing position in said pencil. 110

8. In a pencil, a casing, a removable sectional lead operating unit, means for separably locking the sections of the unit against relative longitudinal movement to each other and means for locking the unit in said casing. 120

9. In a pencil, including a lead-propelling means comprising a removable tubular threaded member, a removable tubular operating member extending into said threaded member and separable therefrom and a 125

130

- lead carrier adapted to be operated by said operating member.
10. In a pencil, including a removable lead-propelling means, comprising a tubular threaded element detachably connected to the body of said pencil, a tubular longitudinally slotted element rotatably and longitudinally slidably in said threaded element and a lead-carrier adapted to travel in said slotted element and to form frictional spring contact between said threaded element and said slotted element to prevent free rotary or longitudinal movement of the same, said tubular slotted element being detachable independently from said threaded element.
11. In a pencil, a barrel, a threaded tubular member having a shoulder on one end freely contacting with the inner surface of said barrel, attaching means on the other end, to secure said threaded member against rotation through said barrel with a space forming a magazine about said threaded member, a tubular operating member detachably, rotatably and longitudinally slid- able in said threaded member, and lead-carrying means adapted to resiliently connect said threaded and operating member to form frictional holding means between the same and a stop to limit longitudinal movement of said operating member.
12. In a pencil, including a removable and separable lead-propelling means, a portion of said propelling means being adapted to cooperate with the pencil body to form a magazine about said propelling means, the operating member of said propelling means extending axially in said pencil being rotatably or longitudinally movable and separable without opening the magazine.
13. In a pencil, a casing having a forward conical end, and a rear open end, a tubular threaded member having a spacing washer on its forward end, and a closure attaching means on its other end, said tubular threaded member cooperating with said casing to form a lead magazine and attached to said casing at its rear open end by said closure, said threaded member being adapted to withdraw and expose marking leads held in said magazine when the same is withdrawn from said casing, and an operating member adapted to extend axially through said threaded member and detachably connected therewith to hold the marking lead in writing position in said pencil.
14. In a pencil, having a casing, a sectional lead-operating unit adapted to be enclosed in said casing, one of said sections being adapted to cooperate with the casing to form a lead compartment having a closure on its rear end adapted to attach said section to said casing and the other of said sections of said operating unit being independently separable from the first section to insert a new marking lead in marking position in said last-named section without opening the lead compartment.
15. In a pencil, including a barrel, a removable lead-propelling means the outer wall of which forms the inner wall of a magazine about said propelling means, the rear end of the inner wall of the magazine forming a closure for the same, actuating means extending through the magazine closure detachably secured by spring tension and extending axially in said pencil, a magazine closure adapted to detachably engage the inner wall of the magazine of said barrel to open the magazine and project the marking leads from the rear end when the magazine is opened.
16. A pencil, a casing, a removable lead operating unit formed of separable sections positioned in said casing to form a magazine thereabout, adapted to project the leads in the magazine out of the rear end thereof when said unit is partially withdrawn, and a resilient lead carrier adapted to form spring tension between said sections.
17. In a pencil, having a lead-propelling means detachable from the casing of said pencil, attaching and spacing means attached to said propelling means to form a magazine space about said propelling means in the pencil casing, an operating member extending axially through said propelling means and independently separable therefrom, said propelling means exposing the contents in the magazine and leaving the casing of the pencil entirely empty when the same is withdrawn therefrom.
18. In a mechanical pencil, a casing, a lead propelling mechanism formed of separable sections, means for holding said sections collectively in or out of said casing and compensating means adapted to form a uniform tension between said sections and to form the lead carrier for said pencil.

In testimony whereof I affix my signature.
HOWARD L. FISCHER.
